UNITED STATES PATENT OFFICE.

BRUNO LAUCKNER, OF OLBERNHAU-GRÜNTHAL, GERMANY, ASSIGNOR TO GROVE F. NEWHARD, OF ST. LOUIS, MISSOURI.

ELASTIC.

No. 919,192.

Specification of Letters Patent.

Patented April 20, 1909.

Application filed April 16, 1908. Serial No. 427,353.

To all whom it may concern:

Be it known that I, BRUNO LAUCKNER, a subject of the German Emperor, and residing at Olbernhau-Grünthal, Germany, have 5 invented new and useful Improvements in Elastics, of which the following is a specification.

This invention relates to garment supporters and like articles comprising a suitable 10 length of fabric and fastening devices at the ends thereof, and particularly to that class of such devices in which the body is composed of an elastic and an inelastic fabric combined.

The object of the invention is to provide 15 garment supporters, including garters, suspenders, hose supporters, and the like, of improved construction wherein the extension of the elastic portion of the body is limited in its elongation by means of the inelastic portion of the body, thus preventing over-stretching which very often takes place in articles of this character.

A further object is to provide means for 20 more securely fastening the ends of the combined fabric to the fastening devices.

With these objects in view the invention consists in the improved construction, arrangement and combination of parts hereinafter fully described and afterward specifically claimed.

In the accompanying drawing, illustrating the invention in detail Figure 1 is a view 25 in elevation of part of an article constructed in accordance with the invention, one fastening device and part of the elastic and inelastic members being shown. Figs. 2, 3, and 4 are detail transverse sectional views illustrating varied forms of the inelastic member. Fig. 5 is a plan view of the clamp 30 for securing the body to the fastening members, before securing it in position. Fig. 6 is a bottom view of the clamp detached but bent into securing form. Fig. 7 is a view in elevation of a completed article the inelastic member being shown as gathered or ruffled up, part of same being broken away.

Like reference characters mark the same parts in all of the figures.

Referring specifically to the drawing, *a* indicates a flat fabric such as a webbing or ribbon which forms the inelastic member of the body of the article and *b* a tube formed longitudinally thereof. In Figs. 1, 2, 3 and 7 but one tube is shown but in Fig. 4 a plurality of parallel tubes may be seen. The

number of such tubes may be varied within reasonable limits. These tubes may be variously constructed, Fig. 2 showing the tube woven with the fabric and Fig. 3 showing the tube formed by securing a suitable strip *c* 60 along one side of the fabric.

The elastic member preferably consists of a wound wire spring *d* which may be nickel- 65 elled or otherwise protected against rust. This spring is inserted in the tube *b* as shown in Fig. 1 and is secured at either end to the fastening means *e*. As shown in Fig. 1, the spring *d* is secured simply by being hooked into a ring *f* on the button yoke *e* but in Figs. 5, 6 and 7, there is shown my special form of 70 clamp for this purpose. This clamp, consists of a metal blank stamped hollow or otherwise rounded out at the places *h*, *i*, *k*. For clamping the end of the spiral spring *d* and attaching it to the fastening device *e*, 75 this blank is bent along the line *x*—*x* of Fig. 1, the tongues *l* being bent at a right angle to close the annulus formed by the rounded portions *i* and the lower tongue *l* extending in between the adjacent turns of the introduced end of the spring, thereby securely holding the latter, the parts *g* being closed together. The little tongues *m* are bent over, as shown in Figs. 6 and 7, so as to hold 80 the two halves of the clamp together. The sleeves formed by the portions *h* freely turn on the cross-bar *n* of the fastening device *e*.

After the ribbon is slid over the spring, it may be gathered, ruffled or shirred, as shown in Fig. 7, and then secured to the fastening 90 means *e*, *e*, by sewing or otherwise to cover the clamps. In use, the elastic member can readily stretch, the gathers of the web giving, until the latter is stretched to its fullest extent, when, by reason of its own inelastic 95 nature, it will prevent further stretching of the elastic member. Upon contraction of the spiral spring, the webbing will readily again shape itself into gathers, as shown. It is not, however, absolutely necessary to 100 gather, ruffle or shirr the fabric but simply to slip over the spring a length of ribbon or webbing of greater length than the spring and the act of placing it upon the spring will gather it until it is of the same length 105 as the spring, this gathering and restretching being possible owing to the fabric being flat on the opposite sides of the tube.

It will be seen from the foregoing that the flat fabric is secured to the fastening means 110

along the whole width of the fabric, and in such a manner as to permit the fastening means to freely swing, and that the spring is also securely held to the fastening means without interfering with its swinging.

What I claim as new is:

1. A garment supporter comprising an inelastic flexible member having a longitudinal tubular portion, and flat portions on opposite sides thereof, an elastic member in said tubular portion shorter than the inelastic member, means for removably fastening the supporter to a garment, and means for independently securing the elastic and inelastic members to the fastening means, substantially as described.

tube and flat portions extending from the opposite sides thereof, an elastic member of less length than the inelastic member and inserted in said tube, a fastening member, a clamp comprising a tubular portion to receive a part of the fastening member, and serving to secure the elastic member to the fastening member, and means for securing the ends of the flat portions of the inelastic member to the fastening member, substantially as described.

In testimony whereof I affix my signature in presence of two witnesses.

BRUNO LAUCKNER.
